DENTAL LABORATORY CASTING RING
INSERT MEANS

Frank J. Fiorella, Tulsa, Okla.

Application May 13, 1947, Serial No. 747,661

2 Claims. (Cl. 22—97)

1

The present invention relates to novel and improved insert means which is especially and properly adapted for use within the confines of a partial denture casting and inlay ring or equivalent form, and an investment or filler which is poured and allowed to harden in said ring; and, the principal object of the invention is to adequately strengthen and reinforce the investment, by way of said insert, at the end portions, which usually protrude and bulge beyond the open ends of the ring, whereby said end portions are sufficiently harnessed and controlled to satisfactorily overcome undue and undesirable expansion of said investment.

A dental laboratory in making partial denture castings of gold and stainless steel, in which tube teeth later are secured, uses, as is common to the trade, an imperforate open-ended metal ring into which is placed a wax pattern of the partial to be cast. When the pattern has been placed in the ring, a casting investment is poured into the ring around the pattern while said ring is in the horizontal position. When the invested pattern in the ring has been sufficiently heated (between 1250° and 1500°) for the casting operation, the wax pattern is melted and eliminated in the customary manner. It is then turned to a vertical position and a crucible, containing the gold or chrome cobalt metal, is placed in conjunction with the sprues leading from the mold. Thus the ring, investment, mold and sprues have been turned from a horizontal to a vertical position in order to fit into a centrifugal casting machine. The molten gold, or other metals, is forced from the crucible into the mold through the channels by centrifugal force.

The heat, which is necessary to effectuate the proper expansion, usually causes a hyperexpansion of the casting investment, so that the ends of the latter bulge slightly beyond the open ends of the ring. The result of this is that the mold itself is enlarged slightly, is therefore imperfect vertically, and does not conform perfectly to the master model. The vertical dimensional changes taking place before the casting is completed causes a high occlusion with the tube teeth that are placed in the casting, and it is necessary to trim the cusp of the teeth down to compensate for this imperfection. The use of the vertical insert controls and equalizes the horizontal and vertical dimensional expansion evenly throughout the mold, thereby minimizing any occlusal rise that may occur.

In carrying out the principles of the instant invention and with a view toward satisfactorily

perfecting gold and equivalent castings, having been produced as above indicated, I provide simple and expedient devices in the form of metal inserts, these being of open-work form and being imbedded in the investment at the proper stage and functioning as suitable reinforcement stays.

In reducing to practice a preferred embodiment, the insert means is of annular form, in general outline and conforms to the surrounding annular investment jacketing ring and the end portions coact with opposite open ends of the ring, whereby and despite the terrific heat applied, the expansion of the investment is equalized.

Another object of the invention is to simplify the dental technique of producing suitably perfected gold inlays and abutments and equivalent partial denture castings for, under ordinary circumstances procedures necessitate making two investments, the first one which is in the form of a thin coating, being placed around the pattern and allowed to set for about ten minutes, and the second investment being made to completely fill the ring with the second mix. It follows that, by using the improved reinforcing inserts, constituting the subject matter of the instant invention, but one investment is necessary.

Other objects and advantages will become more readily apparent from the following description and the accompanying illustrative drawings.

In the drawings, wherein like numerals are employed to designate like parts throughout the views:

Figure 1 is a perspective view of insert means constructed in accordance with the invention showing a sectional construction thereof and showing the sections assembled in a dotted line so-called forming or casting ring;

Fig. 2 is a perspective view similar to Figure 1 but showing a simpler form of insert formed in one piece for inlays and three-quarter abutment castings;

Figure 3 is a group perspective view of sections which go to make up the complete insert;

Figure 4 is a view showing a casting machine bracket, crucible, wax pattern, reinforcing insert means and ring, the latter part appearing in phantom or dotted lines.

Referring first to Figure 4 the letter A designates a casting machine bracket such as is used currently in centrifugal casting machines, B denotes a crucible, C denotes a pattern of wax, D denotes wax or equivalent sprues and these are shown as intervening between the wax pattern

C and crucible B. The customary open ended casting ring is denoted at E, this being shown in dotted lines.

The invention comprises merely the insert means and this may be of sectional construction or unitary construction as shown for example by comparing Figure 1 with Figure 2.

Referring now to the drawings and particularly to the stay and reinforcing means, partly referred to as "insert means," this is shown, as illustrated in Figure 3, as made up of a pair of duplicate companion half-sections 6 and 7. These are brought together in abutting relationship to provide an open-work frame which, looking at either end, is of a general annular form and therefore conforms to and fits within the confines of the surrounding ring E. As each section is the same in construction a description of one will suffice for both. To this end, each section comprises semi-circular flat metal plates 8 and 9 having apertures 10 therein, said plates being connected by spaced stay rods 11 rigidly secured at their lower ends, as at 12, to the lower plate. (see Figure 3) and secured at their opposite or upper ends to ears or lugs 13 provided on marginal portions of the upper plate 8. In practice, the sections are brought together in annular open frame form as shown in Figure 1.

In Figure 2 the stay reinforcing unit or insert is denoted by the numeral 14 and comprises an annular plate 15, a relatively smaller wire or equivalent ring 16 and a pair of diametrically opposite stay rods 17. The ring or annulus 15 is suitably apertured for effectiveness in action as indicated at the points 18. In this form of the invention the forming or casting ring is denoted by the numeral 19.

The insert sections are made of stainless steel and their dimensions depend, of course, upon the size of the ring. The semi-circular portions of said sections are placed in the ring while it is in a horizontal position, at the same time the pattern and investment are placed in the ring. When so placed the semi-circular portions of the inserts form and complete a circle, flush with the side of the open ring into which the molten metal is "thrown." The two ring shaped portions of each of the inserts are then flush with the other open side of the ring. Thus, despite the terrific heat applied, the expansion of the investment is equalized. Otherwise, the lack of this reinforcement oftentimes results in hyperexpansion and consequent vertical imperfection of the mold and casting.

Without these inserts it is usually necessary to make two investments. The first one, which is a thin coating, is placed around the pattern and allowed to set for about ten minutes and then the second investment is made to completely fill the ring with the second mix. With use of these inserts but one investment is necessary.

By use of the insertions it is found that the investment will not hyperexpand or crack even though the investment is heated to a point several hundred degrees over and above the specification of the investment used.

These inserts are particularly efficacious in manufacture of the bi-lateral and other larger palatal bar castings, where the coating of investment is thinner and is therefore more prone

to hyperexpand, crack, and cause imperfections. The control of the vertical dimensional expansion permits a greater degree of horizontal expansion which is necessary to prevent a cross arch bind.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangements of parts may be resorted to in actual practice so long as no departure is made from the invention as claimed.

Having described the invention, what is claimed as new is:

1. As a new article of manufacture, a dental laboratory casting ring insert of the class shown and described, comprising a pair of duplicate half-sections adapted to assume opposed positions in relation to each other and, thus combined, to provide an open-work, frame-like device, said half-sections each including a pair of spaced semi-circular flat metal plates, and rod members connecting said plates in spaced parallelism, the plates of the respective half-sections being disposed in a plane with each other when in use in said casting ring.

2. Means for use in a dental laboratory by a dentist or a technician, to aid in dimensionally perfecting gold or chromium partial castings comprising, a casting ring insert adapted to be placed in a conventional type open-ended cylindrical casting ring, said insert being of a length corresponding to the length of the ring and embodying a pair of spaced parallel end frames substantially flush with the respective open ends of said casting ring functioning to minimize vertical dimensional expansion of the end portions of the mold which is poured in said ring, and said end frames, compared to the diameter of said ring, being relatively wide in cross section, each end frame being composed of opposed and aligned semi-circular apertured plates, the complementary plates of the respective end frames being connected together by rods, said rods, compared to said plates, being relatively small in cross-section and widely spaced from each other to allow for uniform horizontal expansion of the mold so as to effectively control and equalize horizontal and vertical dimensional expansion evenly throughout the mold and to consequently prevent unwarranted harmful vertical hyperexpansion beyond the ends of said casting ring.
